UNITED STATES PATENT OFFICE.

EMIL L. OBERG, OF NEW YORK, N. Y.

CAN-OPENING DEVICE.

1,048,202.

Specification of Letters Patent. Patented Dec. 24, 1912.

Application filed April 26, 1912. Serial No. 693,357.

To all whom it may concern:

Be it known that I, EMIL L. OBERG, a citizen of the United States, residing in the borough of Brooklyn, in the county of 5 Kings, city and State of New York, have invented new and useful Improvements in Can-Opening Devices, of which the following is a specification.

This invention relates to an improved can 10 opening device, and is in the nature of a combined can opener and a cover to serve as a covering for the can when the head or end has been removed, and it is the object of the invention to provide an improved device 15 of this character which is simple and cheap in construction, and efficient in operation.

In carrying out my invention I provide a cover having two different diameters, thus 20 providing an annular flange or shoulder portion to rest and support the cover upon the top of the can, and a portion to snugly fit around the sides of the can, a bail or handle being connected to the portion of the 25 cover of smaller diameter whereby to manipulate the cover in the operation of the cutter and also to place the cover upon and remove it from the can. The cutter is releasably secured to the inside of the cover 30 adjacent to the handle, with the cutting edge projecting down below the flange portion; the securing means for the handle also serving to secure the cutter. This device may also be provided with means to support 35 the head of the can during the cutting operation and to prevent the dropping of the head into the can after it has been cut.

In the drawings accompanying and forming a part of this specification, Figure 1 is 40 a sectional elevation of my improved can opening device applied to a can and showing the operation of cutting the end or head thereof. Fig. 2 is a perspective view of my improved can opening device looking from 45 the side and bottom. Fig. 3 is a perspective view of the cutter. Fig. 4 is an enlarged sectional view of a portion of the cover and the can to illustrate the manner to securely retain the cover on the can; and Fig. 5 is 50 a side elevation of my improved opening device without the support for the head of the can during the cutting operation.

Similar characters of reference designate 55 like parts throughout the different views of the drawings.

The embodiment of my invention illustrated in the drawings comprises a cover of

two different diameters, as shown at 6 and 7, to provide an annular flange or shoulder 8 whereby the cover is supported upon the top of the can, designated in a general way by 9, with the portion 7 projecting down and embracing the sides of the can. A handle or bail 10 of sheet metal with the ends bent at right angles is secured to the 6 outer sides of the smaller portion of the cover, as at 11, 12, with the ends abutting against the shoulder 8.

A knife or cutter 13 is releasably secured to the inner wall of the smaller portion of 70 the cover adjacent to one end of the handle, the means 12 to secure said end of the handle, which may consist of screws; also serving to secure the cutter in place. The body portion of the cutter conforms to the 75 curvature of the can with the cutting edge 14 projecting down beyond the shoulder 8, such cutting edge or edges preferably being in the form of a section of a circle, as shown in Fig. 3, thereby providing a more 80 efficient cutting edge.

In operation the enlarged portion of the cover is placed over the end of the can and by applying pressure to the handle the cutter is forced through the end or head of 85 the can. Rotary motion is then imparted to the cover by the handle, the engagement of the cover portion 7 with the sides of the can preventing any lateral movement of the cover and as the cover is rotated the knife 90 cutting the can. The ends of the handle abutting against the shoulder 8 firmly maintains the cover on the can during the cutting operation. After the top of the can has been removed the opening device may 95 serve as a removable cover for the can.

As is well known the diameters of cans of any standard make, such as condensed milk cans, etc., vary, and in order that the cover will fit snugly and be retained on the 100 can I provide the portion 8 of the cover embracing the sides of the can with indentations or corrugations 15. By this construction the outer edge of said portion 8 will be of greater diameter than the circle described 105 by the projections which may be slightly less than the diameter of the can. By this means the outer edge or un-corrugated portion will readily pass over the can and by forcing the cover down the corrugations 110 will slightly give or spring firmly and yieldingly engaging with the sides of the can.

To support the head of the can during the

cutting operation and to prevent the same from dropping into the can after it has been cut, I provide a headed plunger 19 passing through an aperture in the handle and guided in a bushing 20 in the top of the cover. The lower end of the plunger is pointed and has adjacent to such point one or more convolutions of a thread 22, which is in the nature of a screw thread. The plunger is normally maintained in a raised position by a coiled spring 23 confined between the bushing and a pin passing transversely through the plunger. When the opener is applied to a can to remove the head the plunger is forced downward the point thereof readily passing through the head of the can and by giving the plunger one or more turns the screw threads 22 will firmly engage the metal of the head, and the spring 23 always exerting an upward pull on the plunger and will pull the head away from the can after it is cut. After the head of the can has been entirely cut the cover is removed and by giving a reverse rotation to the plunger the head of the can can be readily released.

Variations may be resorted to within the scope of my invention, and portions of the improvements may be used without others.

Having thus described my invention, I claim:

1. A can opening device, comprising a cover having two different diameters whereby to form a flange to support the cover upon the top of a can with a portion embracing the sides of the can; a handle secured to the portion of the cover of smaller diameter with the ends abutting against the flange; a cutter secured to the inner wall of the portion of the cover of smaller diameter adjacent to one end of the handle, having a double cutting edge projecting beyond the flange portion of the cover; and means to releasably secure the cutter, said means also serving to secure one end of the handle.

2. A can opening device, comprising a cover having two different diameters whereby to form a flange to support the cover upon the top of a can with a portion embracing the sides of the can; a handle secured to the portion of the cover of smaller diameter with the ends abutting against the flange; a cutter secured to the inner wall of the portion of the cover of smaller diameter adjacent to one end of the handle, having a double cutting edge projecting down beyond the flange portion of the cover; means to releasably secure the cutter, said means also serving to secure one end of the handle; and corrugations extending around the portion of the cover of larger diameter, such corrugations commencing at a point within the

edge of such portion of the cover, substantially as and for the purpose specified.

3. A can opening device, comprising a cover having two different diameters whereby to form a flange to support the cover upon the top of a can with a portion embracing the sides of the can; a handle secured to the portion of the cover of smaller diameter with the ends abutting against the flange; a cutter secured to the inner wall of the portion of the cover of smaller diameter adjacent to one end of the handle, having a double cutting edge projecting down beyond the flange portion of the cover; means to releasably secure the cutter, said means also serving to secure one end of the handle; and means to support the head of the can during the cutting operation and to prevent it from dropping into the can after it has been cut.

4. A can opening device, comprising a cover having two different diameters whereby to form a flange to support the cover upon the top of a can with a portion embracing the sides of the can; a handle secured to the portion of the cover of smaller diameter with the ends abutting against the flange; a cutter secured to the inner wall of the portion of the cover of smaller diameter adjacent to one end of the handle, having a double cutting edge projecting down beyond the flange portion of the cover; means to releasably secure the cutter, said means also serving to secure one end of the handle; and means to support the head of the can during the cutting operation and to prevent it from dropping into the can after it has been cut, comprising a headed plunger passing through an aperture in the handle and guided in a bushing in the cover, such plunger provided with a point at its end and one or more convolutions of a screw thread adjacent to the point, and a spring to normally maintain the plunger in its raised position.

5. A can opening device, comprising a cover having two different diameters, as 6 and 7, an intermediate shoulder 8, whereby to support the cover upon the can, the portion of the cover of larger diameter provided with corrugations 15; a handle 10 secured to the part 6 with its ends abutting against the shoulder 8; and a cutter 13 releasably secured to the inner wall of the portion 6 adjacent to one end of the handle with its cutting edge projecting down beyond the shoulder 8, substantially as and for the purpose specified.
